UNITED STATES PATENT OFFICE.

JEAN ALEXANDRE REY, OF PARIS, FRANCE.

CONTROLLING MECHANISM FOR SUBMARINE MINES.

No. 850,967.

Specification of Letters Patent.

Patented April 28, 1907.

Application filed October 10, 1905. Serial No. 282,112.

To all whom it may concern:

Be it known that I, JEAN ALEXANDRE REY, a citizen of the Republic of France, residing at 26 Avenue de Suffren, Paris, France, have 5 invented a new and useful Improvement in Controlling Mechanism for Submarine Mines, which improvement is fully set forth in the following specification.

This invention relates to the firing mechanism of automatic submarine mines or torpedoes in which the explosion occurs either on the impact of a moving vessel or on the explosion of a neighboring mine or counter-mine.

15 It has for its object to prevent explosions through "sympathy" and to render the firing mechanism inert so long as the mine is not at the depth for which it is regulated.

Usually the firing mechanism of a submarine mine is operated through the effect of a shock, whatever may be the details of construction, and is dependent upon the inertia of a metal sphere, a pendulum, or a mass of liquid, this inertia causing a movement of the mechanism in question under the influence of the shock caused by the impact of a moving vessel.

It is evident that if the explosion is caused by the shock of impact of a mass moving at a 30 small speed the explosion will still more certainly be caused by the much greater shock due to the explosion of a neighboring mine or counter-mine. Thus the greater number of the arrangements hitherto used have the 35 great disadvantage of exploding the mine through sympathy—that is to say, when a neighboring mine or counter-mine explodes within a certain range. However, there exists an essential difference between the shock

40 due to the impact of a floating body against a mine and the shock caused by the explosion of a neighboring mine. The shock produced by a floating body takes place without materially modifying the equilibrium of pressure 45 of the liquid mass surrounding the mine. The shock due to an explosion is, on the contrary, derived from the vibrations transmitted by the water, and consequently is only felt when an enormous pressure is developed, commencing with the center of the 50 explosion and diminishing around this center with the square of the distance.

The principle of the different arrangements for controlling the firing mechanism of 55 automatic submarine mines which forms the subject of this invention consists in the em-

ployment of the hydrostatic pressure of the water upon an elastic diaphragm which itself acts upon a longitudinally - movable rod within the mine, the hydrostatic pressure 60 which acts upon the diaphragm being balanced by one or more springs.

In the annexed drawings, which illustrate the invention, Figures 1 and 2 show two arrangements based upon the principle hereinbefore set forth, and Fig. 3 shows its application to a pendulum-controlled mechanism.

1 is a rod controlling the firing mechanism, which is actuated by the inertia of a moving pendulum, Fig. 3, or otherwise, as has been 70 stated above. The rod 1 is for the purpose of locking the firing mechanism (which may be constructed in various ways) to render it inoperative or, on the other hand, to liberate it.

75 The rod 1 receives its motion from an elastic diaphragm 2, fixed to it and acted upon by the pressure of the water passing in through holes in the cap 3. One or more springs act upon the diaphragm 2. Thus in 80 Fig. 1 there are two springs 4 and 5 placed on either side of the rod 1, and in Figs. 2 and 3 there is a single spring 6 surrounding the rod, these springs in both instances serving to counterbalance the thrust of the diaphragms 85 between two given limits of pressure.

In the arrangement shown in Fig. 1 the rod 1 has upon it a forked prolongation 7, which embraces a blade-spring 8, and is provided with a rounded head 9. When the 90 rod 1 is drawn in by the diaphragm 2 in its downward movement, the head 9 strikes against the top 10 of the spring 8, which is flexed by the pressure of the head 9 to an extent calculated beforehand.

95 In Figs. 2 and 3 a truss 11, fixed upon the diaphragm 2 and fast with the rod 1, has a flat lower side 12. 13 is a helical spring resting against a shoulder of the casing 14 and carrying at its free end a disk 15, guided in its longitudinal movement by bolts 16, of which there may be three.

When the diaphragm 2 descends under the influence of the hydrostatic pressure and when the flat portion 12 strikes against the 105 disk 15, the disk compresses the helical spring 13 and the rod is displaced longitudinally to a certain extent.

The function of the leaf-spring 8 in Fig. 1 and the helical springs 13 in Figs. 2 and 3 is 110 to balance the diaphragm against a thrust caused either by a greater hydrostatic pres-

sure or by the pressure due to a neighboring explosion. The first-named springs, 4 and 5 in Fig. 1 and 6 in Figs. 2 and 3, are arranged in such manner as to be capable of regulation 5 or adjustment in order to fix the lower limits of the hydrostatic pressure under which the mine can be exploded, while the second-named springs, 8 in Fig. 1 and 13 in Figs. 2 and 3, are calculated in such manner as to respond 10 to a greater pressure than that necessary to compress the first-named springs. The action of the springs 8 and 13, which correspond to a longitudinal movement of the rod 1, has for its object to render the firing mechanism 15 inoperative as soon as the pressure becomes greater than a given limit, thus to cause the mine to be inoperative when it descends to a certain depth or when it experiences a disturbing effect due to the shock of 20 a neighboring explosion. In other words, the first spring has for its object to unlock the firing mechanism under the action of the diaphragm from a given pressure upward, and the second spring has for its object to 25 lock the firing mechanism when the pressure reaches and surpasses a given maximal limit. The whole system is therefore cocked, as it were, between two limits of pressure—the one a minimal pressure and the other a maximal 30 pressure. The means for adjusting the springs 4 and 5 of Fig. 1 and 6 of Figs. 2 and 3 consists in the former, in this instance, of the screws 5^a, that engage threaded bores in rods 5^b, disposed adjacent to and preferably 35 parallel with the rod 1, and the latter of peripherally-threaded nuts 6^a, that engage threaded bores in extensions 6^b of the caps.

The working of the arrangement shown is as follows: So soon as the mine is placed in 40 the water and the pressure attains even a small amount—for example, corresponding to a depth of fifty centimeters of water—the diaphragm 2 is displaced, the tension of the counter springs 4, 5, and 6 being calculated 45 in such a manner as to allow of this displacement. So soon as the diaphragm is thus displaced the rod 1 sets free the firing mechanism and the mine is then operative—that is to say, it can explode under the influence of a 50 shock the minimum value of which is known. As the mine sinks lower into the water the diaphragm 2 is correspondingly displaced and the rod 1 continues to leave the firing mechanism free. When the pressure of the 55 water has become such that the displacement of the rod 1 allows the head 9, Fig. 1, to touch the spring 8 at the point 10 or the flat portion 12, Fig. 2, to come into contact with the disk 15, the increasing pressure of the water 60 causes the blade-spring 8 or the helical spring 13, according to the arrangement used, to be compressed. The firing mechanism is constructed in such a manner that during the whole movement of the diaphragm 2 up to 65 the point at which the spring 8 or 13 is actu-

ated its liberty of movement is complete. The amount of movement of the diaphragm corresponds, therefore, to the limit values of the hydrostatic pressure at which the mine can explode: So soon as the spring 8 or 13 comes into action, starting with this limit, the movement of the rod 1 locks the firing mechanism and the mine is inoperative. This second portion of the movement of the rod 1 corresponds to a much greater hydrostatic pressure. These results may be obtained with very different arrangements for putting the firing mechanism under the control of the rod 1. Fig. 3 illustrates, for the better understanding of the invention, the 75 application of the arrangement described above to a pendulum-controlled inertia apparatus. 17 is the pendulum, which actuates the “firing mechanism,” properly so called and not shown in the drawings. In the position 80 indicated the diaphragm 2 is at the upper portion of its travel. It does not exert any action upon the rod 1, which is pivoted at 18 to a forked lever 19, working about a pivot 20. The lever 19 carries upon its lower limb 90 a socket 21, engaging a projection 22 on the lower end of the pendulum. In the position shown the pendulum 17 cannot oscillate, and consequently the firing mechanism, which may be of any type, is locked. When the 95 diaphragm 2 descends and moves the rod 1 down, the lever 19 rocks about its pivot 20, and the socket 21 frees the projection 22. The pendulum 17 is now free to oscillate. This release of the pendulum occurs at the 100 smallest depth at which the diaphragm 2 moves in compressing the springs 4 and 5 or 6. When the diaphragm 2 moves in so much that, as explained, the truss 11 compresses the spring 13—i. e., as the rod 1 moves farther in—a collar 23 on the upper portion of the forked lever 19 descends upon the pendulum 17, as shown at 23^a. Under these conditions the pendulum 17 can no longer oscillate and the firing mechanism is locked. 110

The pendulum arrangement above described is merely shown to illustrate the invention. It does not form part of this invention and may be carried out in many different ways. It is shown merely to illustrate the method of action of the rod 1 in the different stages of its movement. 115

This invention, therefore, allows two entirely distinct effects to be obtained. In the first stage of the movement of the rod 1 the hydrostatic pressure may only be small, commencing, for example, at fifty centimeters of water and increasing until it attains ten meters. If, therefore, the mine sinks to a depth of more than ten meters, the second spring 120 (8 or 13) comes into play, the rod 1 continues to fall, and the firing mechanism can no longer be operated. There is thus obtained the first result that the mine is operative only at a certain depth of water, above and below 125 130

which it will not explode. In cases in which the mine is exposed to the explosion of a neighboring mine if the pressure due to the explosion exceeds the limit mentioned above—say 5 ten meters of water—the rod 1 continues, as before, its downward travel and compresses the spring 8 or 13, locking the firing mechanism. This locking is produced exactly at the moment at which the shock due 10 to a neighboring explosion would lead to the firing of the mine itself. The above-described system therefore enables the depth below the surface at which the mine can explode to be regulated and prevents the accidental explosion of drift mines and also prevents the sympathetic explosion of the mine 15 as soon as the hydrostatic pressure produced is greater than that at which the mine can explode. The expression "prevents the explosion of drift mines" is to be understood as meaning that the arrangement disclosed automatically locks the firing mechanism of any mine which on account of the breaking of its anchor-cable floats on the surface 20 of the water or at a depth less than that at which the explosion should take place.

I claim—

1. In a submarine mine, a firing mechanism operative only within predetermined pressures.

2. In a submarine mine, a hydrostatically-controlled firing mechanism operative only within predetermined pressures.

3. The combination with a submarine mine and firing mechanism therefor, of a hydrostatically-actuated member operative beyond extreme pressures for controlling the firing mechanism.

4. The combination with a submarine mine and firing mechanism therefor, of a hydrostatically-actuated member, inert except at a predetermined depth, for controlling the firing mechanism.

5. The combination with a submarine mine and firing mechanism therefor, of a hydrostatically-actuated member for controlling the firing mechanism, and to lock the same at predetermined extreme positions.

6. The combination with a submarine mine and firing mechanism therefor, of a hydrostatically-actuated member for controlling the firing mechanism, said member operating only at a predetermined pressure to release the said mechanism.

7. The combination with a submarine mine and firing mechanism therefor, of a movable member for controlling the firing mechanism, and means actuated by hydrostatic pressure to cause the movable member to render the firing mechanism operative under a mean pressure but inoperative under extreme pressures.

8. The combination with a submarine mine and firing mechanism therefor, of a hydrostatically-actuated member for control-

ling the firing mechanism and operating only within predetermined pressures to release the said mechanism, and means for varying the resistance of the member to movement.

9. The combination with a submarine mine and firing mechanism therefor, of a hydrostatically-actuated member for controlling the firing mechanism, and pressure-opposing means for varying the resistance of the member to movement.

10. The combination with a submarine mine and firing mechanism therefor, of a hydrostatically-actuated member for controlling the firing mechanism, and adjustable pressure-opposing means for varying the resistance of the member to movement.

11. The combination with a submarine mine and firing mechanism therefor, of a hydrostatically-actuated member for controlling the firing mechanism and operating at within predetermined pressures to release the said mechanism, and resilient means for varying the resistance of the member to movement.

12. The combination with a submarine mine and firing mechanism therefor, of a hydrostatically-actuated member for controlling the firing mechanism and operating at within predetermined pressures to release the said mechanism, and adjustable springs disposed in the path of movement of the member for varying its resistance of movement.

13. The combination with a submarine mine, of a casing provided with water-inlets, a flexible diaphragm arranged within the casing, a rod connected with the diaphragm and operating to control the firing mechanism, and springs coacting with the diaphragm, one of which operates to counterbalance the thrust of the diaphragm between two given limits of pressure, and the other to balance a greater thrust caused by an increased hydrostatic pressure.

14. The combination with a submarine mine, of a casing provided with water-inlets, a flexible diaphragm arranged within the casing; a rod connected with the diaphragm and operating to control the firing mechanism, and springs coacting with the diaphragm, one of which operates to counterbalance the thrust of the diaphragm between two given limits of pressure, and the other to balance a greater thrust caused by an increased hydrostatic pressure, one of the springs being adjustable to fix the lower limits of the hydrostatic pressure under which the mine can be exploded.

15. The combination with a submarine mine, of a casing provided with water-inlets, a flexible diaphragm arranged within the casing, a member actuated by the diaphragm for controlling the firing mechanism, and pressure-opposing means coacting with the diaphragm, one of which operates to counterbalance the thrust of the diaphragm between

two given limits of pressure, and the other to balance a greater thrust caused by an increased hydrostatic pressure.

16. The combination with a submarine mine, of a casing provided with water-inlets, a flexible diaphragm arranged within the casing, a member actuated by the diaphragm to control the firing mechanism, and pressure-opposing means coacting with the diaphragm, one of which is adjustable and operates to counterbalance the thrust of the diaphragm between two given limits of pressure, and the other to balance a greater thrust caused by an increased hydrostatic pressure.
17. The combination with a submarine mine, of a casing provided with water-inlets, and a flexible diaphragm arranged within the casing, and operatively connected with the firing mechanism of the mine, the amount of movement of the diaphragm corresponding to the limit values of the hydrostatic pressure at which the mine can explode.
18. The combination with a submarine mine, of a casing provided with water-inlets, a flexible diaphragm arranged within the casing, a rod connected with the diaphragm and operating to control the firing mechanism, and springs coacting with the diaphragm, one of which operates to counterbalance the thrust of the diaphragm up to a given lower

limit of pressure, and the other to balance a greater thrust caused by an increased hydrostatic pressure from a given upper limit of pressure upward.

19. The combination with a submarine mine, of a casing provided with water-inlets, a flexible diaphragm arranged within the casing, a rod connected with the diaphragm and operating to control the firing mechanism, and springs coacting with the diaphragm, one of which operates to counterbalance the thrust of the diaphragm up to a given lower limit of pressure and the other to balance a greater thrust caused by an increased hydrostatic pressure from a given limit of pressure upward, the said springs being adjustable to fix the maximal limit of the hydrostatic pressure under which the mine can be exploded, so that the firing mechanism can be operated when between given limits of pressure and is locked if said pressure is not comprised between said limits.

In testimony whereof I have signed this specification in the presence of two subscribing witnesses.

JEAN ALEXANDRE REY.
